UNITED STATES PATENT OFFICE.

EDWARD THOMPSON MORRISS, OF LETCHWORTH, ENGLAND.

PERAMBULATOR AND THE LIKE.

Application filed March 9, 1925, Serial No. 14,179, and in Great Britain July 17, 1924.

This invention relates to perambulators, mail carts and the like, and has among its objects effectively and resiliently to suspend or support the body without the employment 5 of a frame extending as a whole or substantially from within or beneath the body, and to produce a construction that is neat and compact, and that is adapted conveniently to be kept clean and of good appearance.

10 According to the invention the body of the perambulator, mail-cart or the like is suspended or supported from the front and rear axles by elastic elements or helical springs disposed in opposite positions in sets, so that 15 the slight downward displacement of the body with reference to the axles takes place under the resistance of the respective sets of springs in such manner that they are extended or compressed.

20 According to the invention the axles are advantageously connected together by parallel longitudinal members, which with the axles, may constitute a substantially rectangular frame, so that thus the stresses imposed 25 upon the springs under load are inwardly transmitted to the respective axles and to the frame.

The invention comprises the constructional features hereinafter described.

30 The invention is illustrated by way of example in the accompanying diagrammatic drawings, in which

Figure 1 is a sectional side elevation of a perambulator constructed according to the invention and Figure 2 is a plan of the connected axles illustrated in Figure 1.

Figures 3 and 4 show in side and end elevations a constructional modification.

In carrying the invention into effect according to the modification illustrated in Figures 1 and 2 the body *a* is suspended or supported within the body from the respective axles *c* by two sets of helical springs *p*, one end of the springs *p* of each set being secured 45 at opposite ends of the lower part of the body *a* while the other end of the springs of the respective sets is secured to the axles *c*, whose respective ends pass through oppositely disposed apertures *r* in the lateral walls 50 of the body. The apertures *r* are of such dimensions as to permit to the axles *c*, the necessary freedom of vertical and horizontal movement under road shock. The axles *c* are connected together by longitudinal bars 55 *q* to form part of a rigid frame disposed within the body beneath the seats *n*; while the

helical springs *p* of the respective sets are advantageously oppositely disposed, their respective outer ends being connected to the body *a* at its opposite ends and their inner ends to the respective axles *c*, so that thus the weight of the body *a* is transmitted inwardly to the respective axles *c* through the respective sets of springs, and under road shock the load causes the extension of the springs. By 60 such means the body is suspended from or supported by a relatively small frame whose length is determined by the distance apart of the axles *c*, and the employment of an externally extending frame to which the handle bars are connected, is avoided. Thus the handles may be applied to the body, and the thrust imparted to the perambulator in moving it, is directly transmitted to the frame 65 through the suspension or supporting springs 70 *p* without possibility of the body swinging in the frame and consequent liability of toppling over.

The helical springs *p* may be provided of two, three or other number at each end, 80 and the ends of the oppositely disposed springs of each set are disposed or directed away from the rectangular frame, and the springs may be disposed at a slight upward 85 inclination from the horizontal towards the frame, to the axles of which the inwardly directed ends are connected, as illustrated in Figures 1 and 2.

The helical springs *p*, however, may be set in other positions, that is to say from a position very slightly inclined from the horizontal to a position nearer the vertical, whereby the load is more or less vertically suspended, but it is in general preferred to dispose the helical 90 springs inclined more or less slightly to the horizontal in the manner illustrated in Figure 1, and the springs of the respective sets connected to the corresponding axles in opposite positions and directed away from the frame, as illustrated in those figures, so that 95 thus in pushing the perambulator or mail-cart the respective sets of spiral springs effectively serve to transmit the thrust to the axles and wheels. By such a method of suspension it is possible to dispense with handles applied 100 directly to the frame, and the body while being resiliently supported is firmly held.

The helical springs *p* may be directly secured to the body, or they may be secured thereto by means of brackets such as *p*¹ (Figures 1 and 2) of such a form and disposition as may be required according to the relative

positions of the springs and the body, the final turns of each spring p being applied upon an integral conical part p^2 of a ring p^3 secured by means of a pin p^4 in the bracket p^1 , while 5 the springs p may be connected to the axle merely by the ends of the springs encircling the axle, or by the use of special fittings such as those illustrated in Figure 1 comprising a ring s formed with an integral conical part 10 s^1 which is engaged by the final turns of the spring p .

The helical springs p may be secured or maintained in determined positions on the axles by any suitable means, such as rings secured upon the axle, on which annular grooves are provided within which the ends of the 15 springs may lie.

It will be understood that the rectangular frame formed by the axles c and the longitudinal members q may be constructed in any 20 convenient way, but conveniently the longitudinal members of the frame may be brazed or welded to the respective axles. The longitudinal members q may be tubular as may also 25 the main part of the axles c , which if tubular may be provided with reduced solid ends upon which the road wheels may be applied in known manner.

It will be understood that instead of supporting or suspending the body upon the frame by the use of helical springs, in the manner described links of india rubber may be employed or any other equivalent; and that instead of employing elastic links, links 30 in the form of rods may be employed that may be conveniently pivoted or otherwise connected to the body or to the frame, and resilient elements interposed between the connected axles and the ends of the body, the arrangement being such that the body is thus supported or suspended from a relatively small frame disposed within or immediately beneath the body for the purposes described.

In Figures 3 and 4 are illustrated a modification of the construction shown in Figures 45 1 and 2 in which the rectangular frame comprising the axles c and longitudinal members q , is disposed in close proximity to and immediately beneath the bottom of the body a , and the side walls of the body a at a^2 (Figures 3 and 4), are advantageously downwardly extended below the bottom of the body, so that the greater part of the frame is enclosed or obscured. At each end however 50 the side walls of the body are advantageously formed with recesses t at the positions at which the axles c are disposed, so that thus the outwardly extending ends of the axles are free to move upwardly and horizontally therein under road shock. The recesses t in the side walls of the body may 55 continue in the bottom a^2 of the body, but this is inessential.

In the modification illustrated in Figures

3 and 4, the helical springs p are slightly 65 downwardly inclined and are under tension, and the springs may be provided with ring fittings at their respective ends, or the ends of the springs may be formed into rings or loops, whereby they may be connected to 70 grooved pins u secured to the side wall of the body a and to the axles respectively.

It will be understood that the edges of the recesses t (Figures 3 and 4) and the upper edges of the apertures r may be provided 75 with a lining of rubber or other resilient substance or that buffers or blocks of rubber or other resilient substance may be mounted in determined positions upon the axles, or beneath the body as protection against the 80 undue movement of the axles.

I claim:

1. In perambulators and similar vehicles, means for mounting the body upon the axles comprising the body, axles transversely disposed within the said body, wheels externally mounted at the respective outwardly protruding ends of the said axles and in position beside the said body, means by which the said axles are held immovably in relation to each other to form with the said axles and within the said body a frame in the plane of the said axles, and elastic tension elements connected at their inner ends with the said internal frame and at their outer 85 ends with the said body, the said elastic tension elements being respectively directed away from the said axles and towards the respective ends of the said body by which the said body is connected to and suspended from the said frame whereby the stresses imposed upon the said elastic tension elements by the weight of the said body are transmitted in part to the said internal frame, substantially as hereinbefore described.

2. In perambulators and similar vehicles, means for mounting the body upon the axles comprising the body, axles transversely disposed within the said body, wheels externally mounted at the respective outwardly 110 protruding ends of the said axles, parallel longitudinal members forming with the said axles a quadrilateral frame within the said body and helical tension springs connected at their inner ends with the said internal 115 frame and at their outer ends with the ends of the said body, the said elastic tension elements being respectively directed away from the said frame and towards the respective ends of the said body by which the said body 120 is connected to and suspended from the said frame whereby the stresses imposed upon the said elastic tension elements by the weight of the said body are transmitted in part to the said internal frame, substantially as hereinbefore described.

EDWARD THOMPSON MORRISS.
